SWITCH CONTROL DEVICE

David P. Joffo, New York, N. Y.

Application March 7, 1941, Serial No. 382,348

5 Claims. (Cl. 200—39)

My invention relates to electric circuit controlling devices and more particularly to a time responsive switch, in combination with a conventional clock mechanism for closing an electric circuit to domestic appliances such as radios, electric phonographs, coffee percolator, ultra violet rays, therapeutic lamps, furnace damper control devices, electric light circuits and the like at any pre-set time thereby providing mechanisms and improvements over the conventional 10 clock and similar mechanisms.

In prior devices of similar character in which a conventional clock mechanism is utilized to actuate an electric switch there is a period of approximately three hours in twelve in which the switch cannot be controlled to function at any required time. This is due to the fact that the rise of the cam which actuates the release mechanism occupies about ninety degrees of the cam and the switch mechanism cannot be reset until the cam follower has traveled this rise.

The principal object of my invention is to overcome this disadvantage by applying a novel switch detent and release to a conventional clock mechanism by which the switch may be actuated at any pre-set time during the entire twelve hour cycle of the clock.

A further object is to provide a pair of outlet sockets with the clock, one of which is connected in series with the time controlled switch and the current supply and the other connected directly with the current supply. These sockets may be used together or either may be used independently of the other, for instance to either manually operate a radio receiver or to automatically turn it on at any predetermined time.

Another important object is to provide a time switch which once closed, will remain closed until manually reopened.

A still further object is to provide a device of the above character which may be applied to an existing clock mechanism without material change and therefore inexpensive to manufacture and durable in use.

Other objects and advantages of my invention will be apparent from the following description and drawings to which it refers and in which

Figure 1 is a front elevational view of my device;

Fig. 2 is a side elevational view;

Fig. 3 is a rear elevational view;

Fig. 4 is a vertical transverse sectional view taken on the line 4—4 of Fig. 2 looking in the direction of the arrows;

Fig. 5 is a detached front elevational view of the clock mechanism and associated switch;

Fig. 6 is a horizontal sectional view taken on the line 6—6 of Fig. 1 looking in the direction 5 of the arrows;

Fig. 7 is a vertical cross sectional view taken on the line 7—7 of Fig. 1 looking in the direction of the arrows the clock mechanism being shown in elevation;

Fig. 8 is a schematic view of the wiring;

Fig. 9 is a fragmental sectional view of the switch showing the position of the parts when switch is "off";

Fig. 10 is an end view of Fig. 9;

Fig. 11 is a view similar to Fig. 9 but showing a different position of parts, the switch being still "off";

Fig. 12 is an end view of Fig. 11;

Fig. 13 is a view similar to Figs. 9 and 11 20 showing the parts when switch is "on";

Fig. 14 is an end view of Fig. 13;

Fig. 15 is a face view of a modified form of my device.

Fig. 16 is a side elevational view of that shown 25 in Fig. 15 and

Fig. 17 is a top plan view of Fig. 15.

Referring to the drawings the numeral 1 represents a clock case, the front wall 2 of which is cut out to receive the clock bezel 2a and crystal 30 2b. Suitable feet 3 are provided on the base of the case for maintaining it in an upright position.

Within the case are contained the clock mechanism designated generally as 4, an electric 35 switch 5, the switch actuating mechanism 6, a pair of electric outlet sockets 7 and 8 which project through the rear wall of the case and necessary electrical connections to the switch and sockets.

40 The rear wall 9 of the case 1 is also cut out as at 10 and has attached thereto the back plate 11 of the clock mechanism. Extending through the back plate 11 is a winding key 12, hand setting knob 13, switch pre-set knob 14 and switch cocking lever 15.

The face 16 of the clock is provided with the usual minute and hour hands 16a and 16b, minute graduation and indicia 17 and 18. In the lower part of the face is an arcuate cut out 19, provided with a cross hair or pointer 20, through which may be viewed a setting dial 21 which in the present instance is graduated to represent fifteen minute intervals for a period of twelve hours. Obviously, by suitable gear ratio this 55

time may be extended or reduced to a greater or less time.

As best seen in Fig. 5, the minute pinion 25, on the center shaft of the clock mechanism meshes with a gear and pinion 25a and then with a gear 26 to which is attached a cylindrical cam 27. The cam 27 is provided with a shoulder 27a and a rise 27b. This cam and gear rotate and may move longitudinally on a shaft 28 which extends from directly behind the clock face through the clock mechanism and projects through the back plate 11. The projecting end of this shaft carries the switch setting knob 14.

The extreme forward end of the shaft 28 carries the setting dial 21 and immediately behind it a cam follower 29 which engages the cam 27. The above construction with the exception of the dial 21 is conventional to the usual alarm clock mechanisms.

A flat leaf spring 30, one end of which is anchored as at 31 to the front plate of the clock mechanism has its opposite end bent to extend laterally rearward as at 32 and is provided with a step 33, the purpose of which will be described later. The intermediate portion of the spring 30 engages the rear hub of the gear 26 to force the cam 27 into engagement with the follower 29. Rotative movement of the cam 27 in conjunction with the fixed follower will cause a lateral movement of the cam and consequently the stepped end of the spring 30. This action is also conventional to alarm clock mechanisms being used to actuate the bell hammer release.

The switch 5 may be of usual off-center toggle or snap type and the internal construction is not described in detail. It is, however, provided with a U shaped mounting bracket 40 by which it may be rigidly attached to the clock mechanism.

The operating arm 41 of the switch is provided with an elongated hub 42 and a radially extending arm 43. The arm 43 is adapted to move in the path of the lateral stepped extension 32 of the spring 30. The hub 42 is rigidly attached to a shaft 44 which is slidably and rotatably journaled in the sides of the U shaped bracket 40 and extends laterally therefrom and through an aperture in the back plate 11. The switch cocking lever 15 is attached to the extending end of this shaft 44.

A light compression spring 45 surrounds the hub 42 and is interposed between the rear side of the bracket 40 and a shoulder 46 on the hub to normally force the hub with its arm 43 toward the front side of the bracket. A tension spring 47, one end of which is attached to the free end of the arm 43 and the other to a suitable portion of the clock mechanism as at 48 normally tends to move the switch 5 to its "on" or closed position.

Extending laterally forward from the arm 43, intermediate its ends, is a short pin 50 adapted to engage a notch or step 51 in the forward side of the bracket 40 when the switch is in its cocked or "off" position and when the stepped end 32 of the spring 30 is in its retracted position out of the path of the arm 43 as shown in Figs. 9 and 10. This position occurs when the follower is in engagement with the rise 27b of the cam 27, usually a period of about three hours after the end of the spring 30 has been retracted.

As the end 32 of the spring 30 moves toward the arm 43 it moves the arm rearward until the pin 50 disengages the notch 51. The arm then moves down slightly into engagement with the

step 33 by tension of the spring 47. The plane of the step 33 is slightly above that of the notch 51 to prevent the pin 50 reengaging the notch 51 when the spring 30 is retracted but not sufficient movement of the arm 43 is permitted to move the switch to its "on" position. This change of position of the parts is shown in Figs. 11 and 12.

When the spring 30 is retracted at the pre-set time or when the shoulder 27a of the cam moves past the follower 29 the end 32 moves forward out of the path of the arm 43 allowing the arm to move its full limit and close the switch 5 as shown in Figs. 13 and 14.

The electrical connections to the several parts are schematically shown in Fig. 8. A two wire cable 60, provided on one end with a suitable male connector plug 61, extends through a bushing 62 into the clock case where its wires 63 and 63' are connected to the terminal posts of the outlet socket 8. A conductor 64 connects one of these terminals with one terminal of the outlet socket 7. A conductor 65 is connected to the opposite terminal of the outlet 7 and to one side of the switch 5 and a conductor 66 connects the opposite side of the switch 5 with the second terminal of the outlet 8.

Thus there is provided one outlet connected directly with the source of electric current and one outlet connected to the electric current supply through the time controlled switch.

In operation, if it is desired, for instance, to turn on a radio receiver at a desired time, for example seven o'clock, at any time prior to this the knob 13 is rotated until the proper graduation on the dial 21 coincides with the pointer 20. This moves the cam follower 29 relative to the shoulder 27a of the cam 27.

The current supply cable of the receiver is inserted in the socket 7, the radio switch turned on, and the receiver is turned to the desired station. The cocking lever 15 is then moved to its "off" position to open the switch 5 and disconnect the current supply to the radio. The clock motor then rotates the cam through its chain of gears until the preset time is reached when the follower 29 reaches the shoulder 27a of the cam 27, allowing the end 32 of the spring 30 to move away from the arm 43 and permit the tension of the spring 47 to close the switch 5 and complete the electric circuit to the receiver.

The timer may then, if desired, be immediately reset for a future program without interruption to the one being broadcast and before or after its expiration the receiver retuned, if desired, and the switch 5 recocked.

The other outlet socket 8 may be used for conventional connection of the receiver or simultaneous use as a convenience outlet for electric current to other appliances.

Other functions as set forth above and yet other functions which will be readily apparent to its users may be performed by this novel time switch.

In the modified form of my invention illustrated in Figs. 15, 16 and 17, I may employ the same mechanism heretofore described except that it is constructed to a smaller scale. Here the case or housing 100 is made of an insulating material as Bakelite or other plastic having dielectric properties and comprises a cylindrical body portion 101, the front of which is fitted with a bezel 102 and glass 103. Behind the glass 103 may be viewed the clock dial 104 and the graduated setting dial 105. The setting dial 105 is

viewed through an arcuate aperture 106 provided with a pointer 107.

Projecting radially upward from the periphery of the body 101 is a clock winding and setting stem 108. On the opposite side of the periphery of the casing 101 is an integral housing 109 which contains the switch 5 and projecting therefrom is a switch cocking lever 110.

On opposite sides of the body 101 are bosses 111 and 112 provided with apertures to form 10 outlet sockets similar to the sockets 7 and 8.

The rear face of the body 101 carries a projection 113 provided with a pair of connector prongs 114 and 115 by which the device may be electrically connected into a household convenience outlet. A presetting knob 116 projects from the face of the clock to set the time of switch actuation, such time being indicated on the dial 105.

As shown in Fig. 8 an indicator lamp may be electrically connected in parallel with the switch 5 to give a visual indication when the switch is on. This lamp is positioned behind a jewel 11 in the face of the block as depicted in Fig. 1. This light also serves the purpose of a visual reminder apart from the normal function of the device. The release member 30, since as stated above is a part of a conventional clock mechanism, may be used as a detent and release for an alarm hammer should it be desired to incorporate an alarm mechanism with the clock.

Thus I provide a time switch which is small and inconspicuous and which may be used in place of the conventional multiple socket for electrically connecting several appliances, one of which may be turned on at any preset time.

While for purposes of illustration I have disclosed one type of clock mechanism and a single type of switch it is obvious that this construction may be changed without departing from the spirit of the invention. Moreover, variations in the structure of the means for retaining the actuating arm may be made without departing from the underlying concept of the invention.

It is to be understood that this invention is to be limited only by the prior art and the scope of the appended claims.

I claim:

1. In a device for controlling current supply to electrically operated devices, a clock mechanism, a switch, a support for the switch, a lever journalled for movement on the support to actuate the switch, a pin on the lever, a detent on the support to engage the pin and a second detent movable into and out of the path of movement of the lever by the clock mechanism to release the pin from the first detent and engage with the lever said second detent being moved out of the path of the lever by a further movement of the clock mechanism at a predetermined time.

2. In a device for controlling current supply to electrically operated devices, a clock mechanism, a switch, a support for the switch, a lever journalled for movement on the support to actuate the switch, a pin on the lever, a detent on the support to engage the pin, a second detent movable into and out of the path of movement

5 of the lever by the clock mechanism to release the pin from the first detent and engage with the lever, said second detent being moved out of the path of the lever by a further movement of the clock mechanism at a predetermined time and tensioning means associated with the lever to move the switch to its closed position when the second detent has released the lever.

3. In a device for controlling current supply to electrically operated devices, a clock mechanism, a switch, a support for the switch, a lever journalled for movement on the support to actuate the switch, a pin on the lever, a detent on the support to engage the pin, a second detent movable into and out of the path of movement of the lever by the clock mechanism to release the pin from the first detent and engage with the lever, said second detent being moved out of the path of the lever by a further movement of the clock mechanism at a predetermined time, tensioning means associated with the lever to move the switch to its closed position when the second detent has released the lever and manual means for moving the lever to a position 20 whereby it will be engaged by the first mentioned detent.

4. In a device for controlling current supply to electrically operated devices, a clock mechanism, a switch, a support for the switch, a lever journalled for movement on the support to actuate the switch, a pin on the lever, a detent on the support to engage the pin, a second detent movable into and out of the path of movement of the lever, a cam to actuate said second detent, said cam being rotated by the clock mechanism and a cam follower associated with the cam and adapted to impart a reciprocating motion thereto, said second detent being moved into the path of movement of the lever by the reciprocating motion of the cam to release the pin from the first detent and engage the lever and said second detent being moved out of the path of the lever by a further movement of the cam at a predetermined time.

5. In a device for controlling current supply to electrically operated devices, a clock mechanism, a switch, a support for the switch, a lever journalled for movement on the support to actuate the switch, a pin on the lever, a detent on the support to engage the pin, a second detent movable into and out of the path of movement of the lever, a cam to actuate said second detent, said cam being rotated by the clock mechanism, a cam follower associated with the cam and adapted to impart a reciprocating motion thereto, said second detent being moved into the path of movement of the lever by the reciprocating motion of the cam to release the pin from the first detent and engage the lever and said second detent being moved out of the path of the lever by a further movement of the cam at a predetermined time, manual means to adjust the follower relative to the face of the cam and visual means to indicate the position of the follower relative to the face of the cam.

DAVID P. JOFFO.
